DEHYDRATING APPARATUS

Robert G. Fisher, Goplay, Pa.

Application May 19, 1953, Serial No. 355,993

9 Claims. (Cl. 34—87)

1

My invention relates to apparatus for dehydrating, drying and comminuting various materials.

A primary object of the invention is to provide dehydrating, or drying apparatus for various crops, such as corn, beans, alfalfa, and the like, but also equally useful in the treatment of various other divided materials, such as certain fertilizers and the like.

A further important object is to provide in apparatus of the above mentioned character novel means for regulating the flow of material through the apparatus, while the material is under treatment.

A further object is to provide in a drying or dehydrating apparatus a series of agitating and material flow regulating vanes, which are adjustable in unison by the operator while the apparatus is in operation.

A further important object of the invention is to provide a dehydrator for grains and the like, wherein the flow of the grains through the dehydrator is assisted by gravity.

A still further object is to provide in apparatus of the above mentioned character, means for synchronizing the flow of granular material into and out of the apparatus, during its operation.

A still further object of the invention is to provide a dehydrating apparatus which is simplified, rugged and durable in construction, and reliable and efficient in operation.

Other objects and advantages of the invention will be apparent during the course of the following description.

In the accompanying drawings, forming a part of this application, and in which like numerals are employed to designate like parts throughout the same,

Figure 1 is a perspective view of dehydrating or drying apparatus.

Figure 1a is an exploded perspective view of material discharge means.

Figure 2 is a central vertical longitudinal section through the same.

Figure 3 is a transverse vertical section taken substantially on line 3—3 of Figure 2.

Figure 4 is a similar section taken on line 4—4 of Figure 2, parts in elevation.

Figure 5 is a similar section taken on line 5—5 of Figure 2.

Figure 6 is a similar section taken on line 6—6 of Figure 2.

Figure 7 is a similar section taken on line 7—7 of Figure 2, and.

Figure 8 is an enlarged fragmentary elevational view of adjustable vanes and associated elements taken substantially on line 8—8 of Figure 4.

2

In the drawings, where for the purpose of illustration is shown a preferred embodiment of my invention, the numeral 15 designates a horizontal cylindrical steel casing or shell, forming the body portion of the apparatus. The cylindrical casing 15 has vertical end supports 16 and 17 rigidly secured thereto in any suitable manner, for maintaining the casing spaced a suitable distance above a floor or the like, upon which the apparatus rests.

The opposite ends of the cylindrical casing 15 are formed open, and removable steel cover plates 18 and 19 are provided, and rigidly secured to the ends of the casing by bolts 20 or the like, the plates 18 and 19 serving to cover the open ends of the casing 15.

A pedestal or stand 21 is fixedly secured to the floor and spaced a considerable distance from the end support 16, Figure 1. A first bearing 22 is fixedly mounted upon the top of the pedestal 21, with its bore in axial alignment with the longitudinal axis of the cylindrical casing 15. A horizontal ledge or shelf 23 is rigidly secured to the end plate 19, and preferably formed integral therewith and arranged at the elevation of the top of the pedestal 21. A second bearing 24 is fixedly mounted upon the shelf 23 at the elevation of the bearing 22, and having its bore in axial alignment therewith.

A horizontal rotatable shaft 25 is journaled within the bearings 22 and 24, and extends axially through the casing 15, as shown. The shaft 25 is held against axial movement by means of thrust collars 26, secured to the rotatable shaft 25, adjacent to the outer ends of the bearings 22 and 24 by set-screws. A first spider 27 is rigidly secured to the shaft 25 for rotation therewith a substantial distance inwardly of the cover plate 18, Figure 2, and this spider comprises a hub 28 receiving the shaft 25 and rigidly secured thereto by a set-screw or the like. The spider 27 further comprises radial spokes 29 having their inner ends rigidly secured to the hub 28, and an outer annular ring 30, L-shaped in cross-section is rigidly secured to the outer ends of the spokes 29. The spider ring 30 has a horizontal cylindrical portion or web 31, spaced radially inwardly of the sidewall of casing 15, and a radial flange 32, the periphery of which is arranged close to the inner face of the casing sidewall, and preferably slidably contacts the same. The entire spider 27 is thus arranged within the cylindrical casing 15 for rotation with the shaft 25. A pair of opposed annular sealing rings 33, L-shaped in cross-section are rigidly secured to the opposite sides of the radial flange 32 for rotation there-

with, and these rings preferably slidably engage the inner surface of the sidewall of casing 15, Figure 2.

A second spider 34, somewhat smaller in diameter than the spider 27 is spaced inwardly of the cover plate 18, and arranged within the casing 15 for rotation with the shaft 25. The spider 34 comprises a hub 35, rigidly secured to the shaft 25 by a set screw or the like, and radial spokes 36 have their inner ends rigidly secured to the hub 35, and their outer ends rigidly secured to a rigid annular band or ring 37. The spiders 27 and 34 are spaced apart axially within the casing 15 a substantial distance, as shown in Figure 2.

A slightly conically tapered foraminous sleeve or wire mesh screen 38 of considerable rigidity is received within the annular band 37 of the spider 34 and rigidly secured therein by welding or the like. The screen 38 is also received within the cylindrical portion 31 of the spider ring 30, and rigidly secured therein by welding or the like, and one end of the screen 38 terminates at the radial flange 32 of the ring 30, Figure 2. The other end of the screen 38 is spaced axially beyond the annular band 37, and terminates near and inwardly of the cover plate 18. This end of the screen 38 carries an annular reinforcing ring 39, permanently secured thereto by welding or the like, and the ring 39 preferably slidably engages the cover plate 18.

A plurality of circumferentially equidistantly spaced longitudinal anchor bars 40, preferably four in number are arranged adjacent to the outside of the screen 38, and have their ends rigidly secured to the annular band 37 and ring portion 31, respectively, by means of screws 41, welding, or the like. Short radial pivot pins or elements 42 are journaled within openings formed in the anchor bars 40, and each anchor bar preferably carries three of the pivot pins 42 in equidistantly longitudinally spaced relation, as shown. A corresponding number of material agitating and flow control blades or vanes 43 are rigidly secured to the inner ends of the pivot pins 42 of each anchor bar 40. The vanes 43 are arranged near and spaced slightly from the inner surface of the screen 38, and each vane 43 comprises a flat radial body portion 44, and a relatively short inner circumferential extension or lip 45, integral with the body portion 44 and spaced radially inwardly of the screen 38 a considerable distance. The lips 45 of the vanes 43 are likewise spaced a considerable distance radially outwardly of the rotatable shaft 25.

The vanes 43 are thus arranged in sets of three, adjacent to the four anchor bars 40, and inwardly thereof, so that there is a total of twelve of the vanes 43 in the preferred embodiment of the apparatus shown in the drawings. I wish to point out however, that the apparatus is not limited to any precise number of the vanes 43, and fewer or more of the vanes may be employed in each set, adjacent to the anchor bars 44. The vanes in each set are preferably of the same length, Figure 2, and the lengths of the vanes are such that when the vanes extend longitudinally of the conically tapered screen 38, their ends substantially abut or contact as shown. When extending longitudinally of the screen 38, the vanes of each set extend throughout substantially the full distance between the spiders 27 and 34, Figure 2.

A corresponding number of short operating links 46 are rigidly secured to the outer ends of

the pivot pins 42, outwardly of the anchor bars 40, and these short links 46 extend generally circumferentially of the screen 38 within the space between the screen and the sidewall of the casing 15. The links 46 of each set of vanes 43 are connected by common longitudinal operating bars or links 47, pivotally secured at 48 to the ends of the short links 46 remote from the pivot pins 42. The common links 47 are twisted near corresponding ends, as indicated at 49 to form relatively short end portions 50, arranged in generally radial planes relative to the cylindrical casing 15. The link portions 50 extend through openings or slots 51 in the radial flange 32, and longitudinally beyond the adjacent end of the screen 38. A corresponding number, or four fixed fulcrum plates 52 are spaced radially inwardly of the common links 47 and extend longitudinally beyond the spider ring 30, Figure 2. The fulcrum plates 52 have their inner ends projecting into the spider ring 30, as shown, and are rigidly secured to the spider ring by welding or the like. The other corresponding ends of the fulcrum plates 52 terminate in alignment, substantially midway between the end cover plate 18 and spider ring 30. The fulcrum plates 52 are disposed in the same radial planes as the link portions 50 with which they are associated, and are substantially parallel therewith.

Intermediate generally radial operating levers or links 53 have their outer ends pivoted at 54 to the adjacent ends of the common longitudinal links 47. The intermediate links 53 are pivoted near and outwardly of their longitudinal centers to the ends of the fixed fulcrum plates 52, as indicated at 55, Figure 2. The inner ends of the intermediate links 53 terminate close to the shaft 25, and are pivoted at 56 to short generally longitudinal walking links or plates 57. These short walking links 57 have their other corresponding ends pivoted at 58 to radial ears 59, formed integrally upon the inner end of a longitudinally shiftable clutch sleeve 60, in turn slidably mounted upon the rotatable shaft 25 and adapted to turn therewith and to move longitudinally thereon.

The end cover plate 18 has a central cylindrical tubular extension 61, provided at its end with a removable cover plate 62, and the tubular extension 61 is preferably formed integral with the end cover plate 18, Figure 2. The cover plate 62 has a central opening 63, slidably receiving the shiftable clutch sleeve 60. The tubular extension 61 and cover plate 62 define an enclosure 55 or passage for the short walking links 57, and associated elements, which are shiftable longitudinally outwardly of the end cover plate 18 in certain adjusted positions of the vanes 43, as will be more fully described hereinafter. The outer end of the clutch sleeve 60 carries an enlarged integral head 64, arranged between the bearing 22 and cover plate 62. This head 64 has an annular groove 65 formed in its periphery, slidably receiving a pair of diametrically opposed pins or lugs 66, rigidly secured to a generally U-shaped yoke 67, which straddles the head 64 of clutch sleeve 60. The yoke 67 is preferably integrally secured to a vane adjusting lever or handle 68, which extends transversely beyond one side of the shaft 25 and is horizontally disposed. The horizontal lever 68 is pivoted between its ends for horizontal swinging movement to a support plate or block 69, as shown at 70, Figure 3. The support plate 69 preferably has one end rigidly secured to the top of pedestal 21, as at 71, Figure

1, and the support plate 69 may be formed integral with the top of the pedestal 21, as indicated. The opposite end of the support plate 69 abuts the end cover plate 18, and is rigidly secured thereto in any suitable manner.

It may now be seen that the apparatus comprises a rotor including the rotatable shaft 25, spider rings 27 and 34, screen 38, adjustable vanes 43 and the above described linkage for operating the vanes 43, including the longitudinally shiftable clutch sleeve 60. This rotor is journaled upon the bearings 22 and 24, and except for the outer end portion of the clutch sleeve 60 operates entirely within the stationary casing 15.

In order to turn the shaft 25 during the operation of the apparatus, I mount a relatively large grooved pulley 71 upon the rotatable shaft 25 near and outwardly of the pedestal 21. This pulley is rigidly secured to the shaft 25 for rotation therewith by a set screw 72 or the like. A stationary variable speed motor and gear speed reducer unit 73 of conventional construction is arranged near the end of the apparatus having the pulley 71, and the unit 73 drives a grooved pulley 74, carried thereby in radial alignment with the pulley 71, Figure 2, and operatively connected therewith by a belt 75.

An L-shaped hot air inlet pipe 76 opens into the bottom of the cylindrical casing 15 near the end of the same having the support 17. The outer end of the pipe 76 is adapted for connection with the heating flue of a hot air furnace, oil burner, or the like, not shown. I provide an adjustable damper 77 in the hot air inlet pipe 76, to facilitate the introduction of some cold air into the pipe 76 when desired.

An L-shaped exhaust pipe 78 for moisture laden air opens into the top of the casing 15 near its opposite end, and between the end cover plate 18 and spider ring 30. The space between the end cover plate 18 and spider ring 30 constitutes a chamber or reservoir for the moisture laden air to be exhausted through the pipe 78. The exhaust pipe 78 is adapted for connection with a suitable exhaust fan, not shown, which serves to maintain a suitable flow of heated air through the casing 15 during the operation of the apparatus. If desired, to further aid in circulating heated air through the apparatus, a blower, not shown, may be connected with the air inlet pipe 76. The pipes 76 and 78 are both horizontal, and extend transversely of the casing 15, as shown.

An upwardly directed inlet duct or pipe 79 for the material being dehydrated opens through the end cover plate 19 and is rigidly secured thereto. The end 80 of the pipe 79 preferably projects slightly inside of the adjacent open end of the rotary screen 38, for delivering the grain, or the like centrally therein. The pipe 79 has rigidly secured to its upper end an adjustable metering valve casing 81, having a discharge opening 82 registering with the top of the pipe 79, Figure 2. The metering valve casing 81 contains a rotary valve element 83 having an opening or port 84, shiftable into and out of registration or partial registration with the opening 82, to regulate the flow of material to the pipe 79. The metering valve may be of conventional construction, and accordingly, only a fragmentary portion of the valve is illustrated in Figures 1 and 2.

In order to synchronize the adjustment of the metering valve element 83 with the adjustment of the vanes 43, which regulate the flow of material through the screen 38, I provide a longitudinally shiftable connecting rod 85, arranged ad-

jacent to the outside of casing 15 and extending longitudinally thereof and slidably engaging through aligned guide openings 86, formed in the marginal portions of the end cover plates 18 and 19 and the companion end flanges of the casing 15. One end of the longitudinal shiftable connecting rod 85 has a pivotal slotted connection at 87 with the horizontal swingable lever 68, outwardly of the pivot 70 of the lever 68. The opposite end of the connecting rod 85 is pivoted at 88 to the lower end of a vertical swingable lever 89, pivoted between its ends as at 90 to a fixed lug 91, formed upon the end cover plate 19, Figure 1. The upper end of the pivoted lever 89 has a pivotal slotted connection at 92 with a depending vertically swingable crank or lever 93, having its upper end rigidly secured at 94 to the rotary metering valve element 83. The arrangement is such that swinging of the lever 68 about its pivot 70 will effect the simultaneous adjustment of the pivoted vanes 43 and rotary metering valve element 83, to thereby synchronize or equalize the flow of material into and out of the apparatus.

A short depending discharge chute 95 is integrally formed upon the bottom of the casing 15, substantially below the exhaust pipe 78, and opening into the casing between the end cover plate 18 and sealing spider ring 30. The lower end of the discharge chute 95 has a horizontal rectangular frame 96 rigidly secured thereto, and a vertically swingable dump or trap door 97 is provided to cover the opening 98 of the frame 96. The trap door 97 is provided at one end with a hinge knuckle 99, receiving a rock shaft or pin 100, rigidly secured therein. The rock shaft 100 is freely journalled for rotation within aligned openings 101 formed in the frame 96, upon opposite sides of the trap door 97, the trap door being fast upon the rock shaft 100 and rotatable therewith relative to the discharge chute 95. The rock shaft 100 projects laterally beyond one side of the frame 96, and has a transverse screw threaded rod 102 rigidly secured to its end by welding or the like, and arranged at right angles thereto and extending beyond opposite sides of the rock shaft 100, see Figure 1. The screw threaded rod 102 carries a pair of adjustable weights 103, having screw threaded engagement therewith, and arranged upon opposite sides of the rock shaft 100. By means of this arrangement, the trap door 97 may be adjusted to open downwardly when a pre-determined amount of dehydrated material, such as dehydrated grain, has been deposited upon the trap door, after discharging from the open end of the screen 38 adjacent to the discharge chute 95. The dehydrated material discharging through the chute 95 may be collected in suitable bins, or upon a movable belt or the like, not shown. A dial-type thermometer 104 of conventional construction is mounted upon a short upstanding tubular neck 105, formed integral with the casing 15 near the end of the same adjacent the end cover plate 19. The tubular neck 105 places the thermometer 104 in direct communication with the hot air within the casing 15, so that the temperature of the apparatus may be observed.

The casing 15 is provided in its bottom, near its longitudinal center with a large cleanout opening 106, covered by a removable cover plate 101, preferably formed of transparent material such as Pyrex glass, or the like.

Operation

The material intake pipe 79 having the metering valve element 83 connected therein is placed

in communication with a grain hopper, fertilizer hopper or like source of supply of material to be dehydrated. The material gravitates through the pipe 79 to the smaller end of the conically tapered rotary screen 38, Figure 2, and the flow of material through the pipe 79 will be regulated by adjustment of the rotary metering valve element 83, whose metering aperture 84 may register or partially register with the opening 82.

The rotor including shaft 25, tubular screen 38 and associated elements revolves continuously at a relatively slow speed during the operation of the machine, and is driven by the motor-speed reducer unit 73. Heated air from the hot air furnace or the like circulates continuously through the casing 15 and screen 38. As previously stated, the heated air enters the apparatus through the pipe 76, and flows longitudinally through the casing 15 and is exhausted along with the moisture extracted from the material being treated through the exhaust pipe 78.

The rotary screen 38 subjects the material being treated to a continuous tumbling and agitation, as the material passes longitudinally through the screen. The screen 38 becomes larger or flares conically toward its discharge end, so that gravity will assist the passage of the material longitudinally through the screen. While the material is passing through the screen 38, it co-mingles thoroughly with the hot air inside of the casing 15 and becomes dehydrated to the desired extent, the moisture laden air tending to collect in the space between the end cover plate 18 and ring 30, prior to exhausting through the pipe 78. The dehydrated material finally tumbles from the discharge end of the rotating screen 38 and falls upon the pivoted trap door 81, which opens to dump the material, when a pre-determined weight of the same accumulates upon the trap door.

The rate of discharge of the treated material from the apparatus will depend upon the speed with which the material passes through the rotary screen 38, and this will in turn be determined by the relative moisture content of the given material, and the degree of dehydration which it is desired to effect. In any event, the rate of flow of the material through the apparatus may be regulated by angular adjustment of the several sets of vanes 43, and these vanes serve the dual purpose of speeding up or slowing down the rate of flow of the material through the screen 38, and simultaneously subjecting the material to a continuous tumbling and comminuting action within the revolving screen 38.

The vanes 43 and all of their associated adjustment linkage revolve with the screen 38 and shaft 25. The adjustment or pivoting of all four sets of the vanes 43 about their pivots 42 may be simultaneously effected by swinging the lever 68 upon its pivot 70 at any time during the operation of the machine, and while the screen or tumbler 38 is rotating. When the pivoted vanes 43 are simultaneously adjusted or tilted in one direction relative to the longitudinal axis of rotation of the screen 38, the material moving longitudinally through the screen will be retarded or slowed. When the vanes are tilted in the opposite direction, the material will pass longitudinally through the screen 38 with increased speed, and it will of course depend upon the direction of rotation of the shaft 25 for determining which way to tilt the vanes 43 to retard or speed up the flow of material through the screen 38, as should be obvious. At no time is

it necessary to stop the rotation of the screen 38 to adjust the angle of the vanes 43, and the operator need not, and in fact, cannot place his hand inside of the casing 15, which is entirely closed. This renders the apparatus safe to operate. The adjustment of all four sets of vanes 43 is simultaneously effected by means of the lever 68, as previously stated, from outside of the casing 15.

For a given setting or adjustment of the vanes 43, a given amount of the dehydrated material will be discharged through the chute 95 in a specified time. It is desirable that the same amount of material pass into the apparatus through the pipe 79 during the same time interval. To accomplish this, the control lever 68, when shifted to adjust the angle of inclination of the vanes 43, simultaneously effects the adjustment of the rotary metering valve element 83, to bring the opening 84 into the proper degree of registration with the opening 82 to supply the proper amount of material to the pipe 79, to replenish the material which has discharged through the chute 95. The lever 68 when swung in either direction for tilting the vanes 43 in either direction will simultaneously shift the connecting rod 85 one way or the other longitudinally of the casing 15. This will cause the lever 89 and slotted crank 93 to turn one way or the other, for increasing or decreasing the degree of registration of the opening 84 with the opening 82.

It should be mentioned that the radial flange 32 and sealing rings 33 divide the casing 15 substantially into two compartments for the hot air flowing through the same. As previously mentioned, the relatively small compartment to the left of the ring 30 in Figure 2 serves as a collection chamber for the moisture laden hot air to be exhausted through the pipe 78. The compartment of the casing 15 to the right of the ring 30 in Figure 2 is the dehydrating compartment of the apparatus, where the dry heated air actually co-mingles with the material in the screen or tumbler 38 and effects the dehydrating or drying of the material. The heated air entering this compartment through the pipe 76 cannot pass the flange 32 and rings 33 to the smaller exhaust reservoir or compartment, but must flow radially inwardly through the screen 38 and then longitudinally through the open discharge end of the screen, which is the left hand end in Figure 2. With this arrangement, a thorough mixing or co-mingling of the heated air with the material takes place, and the dehydrating is very effective. Any particles of the material being treated which happen to sift radially through the screen 38 will collect on the bottom of the casing 15, and may be cleaned out through the opening 106.

The apparatus is obviously capable of use for dehydrating a wide variety of materials, such as various crops and grain, fertilizers, and the like.

It is to be understood that the form of the invention, herewith shown and described is to be taken as a preferred example of the same, and that various changes in the shape, size and arrangement of parts may be resorted to, without departing from the spirit of the invention or scope of the subjoined claims.

Having thus described my invention, I claim:

1. Dehydrating apparatus comprising a casing adapted to receive a heating medium, a shaft journaled upon the casing for rotation and extending into the casing and beyond one end of the casing, a perforated sleeve arranged within

the casing and secured to the shaft for rotation therewith and having material intake and discharge ends, sets of vanes pivotally mounted within the sleeve for rotation therewith, the sets being spaced circumferentially about the sleeve, operating linkages connected with the sets of vanes to effect pivotal adjustment of the vanes and rotatable with the sleeve and shaft, an element slidably mounted upon the shaft and connected with all of the linkages to operate the same when the element is shifted longitudinally of the shaft, said element extending outside of the casing, and a movable operating member connected with the element to shift the element longitudinally of the shaft when the shaft is rotating or at rest.

2. Dehydrating apparatus comprising an elongated generally horizontal casing having inlet and exhaust openings near its opposite ends for a fluid heating medium, an upwardly extending material inlet duct connected with one end of the casing and leading into the casing, a metering valve element connected with the material inlet duct and adjustable to regulate the passage of material through the duct to the casing, a foraminous tubular element journaled within the elongated casing for rotation and extending throughout a major portion of the length of the casing and having a material inlet end communicating with said material inlet duct and a discharge end, the casing being provided in its bottom near the discharge end of the tubular element with a material outlet opening, angularly adjustable vanes arranged within said tubular element and rotatable therewith and adapted to retard or speed up the passage of the material longitudinally through said tubular element toward its discharge end, mechanical means connected with the vanes to angularly adjust the same in unison while the tubular element rotates and operable from outside of the casing, and means connected with said mechanical means and metering valve element and synchronizing the adjustment of the metering valve element and vanes, whereby substantially the same amount of material will be fed into the apparatus through the material inlet duct as passes out through the material outlet opening of the casing.

3. Dehydrating apparatus for divided material comprising a casing having inlet and exhaust openings for a fluid heating medium, an upwardly directed material intake duct connected with the casing and leading into the same, an adjustable metering valve element connected with said intake duct to regulate the flow of divided material by gravity through the same, a sleeve rotatably mounted within the casing and having openings permitting the fluid heating medium to circulate within the sleeve and inlet and discharge openings for said material, the inlet opening of the rotatable sleeve being adapted to receive the divided material from said intake duct, the casing having a material discharge opening near the discharge opening of the sleeve, sets of pivoted agitator blades mounted within said sleeve and rotatable therewith and adjustable to retard or speed up the passage of the material longitudinally through said sleeve, a linkage connected with each set of pivoted agitator blades to effect their pivotal adjustment in unison, the linkages rotating with said sleeve, an element connected with all of said linkages and rotatable therewith and shiftable axially of the rotatable sleeve for operating the linkages in

unison, a pivoted operating member having swivelled connection with said element and adapted to shift the element axially of the sleeve, and a linkage connecting the pivoted operating member and metering valve element so that the metering valve element is adjusted in unison with the sets of pivoted agitator blades.

4. Apparatus of the class described comprising a casing adapted to receive a fluid heating medium, a shaft journaled upon the casing for rotation and extending inside the casing and exteriorly thereof, a sleeve secured to the shaft within the casing for rotation therewith and being apertured to permit circulation of the fluid heating means within the sleeve, sets of longitudinally spaced angularly adjustable agitator blades pivoted to the sidewall of the sleeve and extending generally radially into the sleeve and bodily carried by the sleeve, the sets of blades being circumferentially spaced about the sleeve, short operating cranks secured to the angularly adjustable blades in each set and arranged outwardly of the sidewall of the sleeve, a common longitudinally shiftable operating bar pivotally connected with the short cranks of each set of blades and extending longitudinally of the sleeve, pivoted cross links connected with corresponding ends of the common operating bars near one end of the rotatable sleeve, a clutch sleeve slidably mounted upon the rotatable shaft and connected with the pivoted cross lengths to operate the same in unison, the clutch sleeve extending outside of the casing, and a pivoted operating lever having swivelled connection with the clutch sleeve to effect longitudinal adjustment of the same while the shaft and clutch sleeve are rotating.

5. Dehydrating apparatus comprising a casing having inlet and outlet openings for a fluid heating medium, a perforated sleeve journaled within the casing for rotation and having material inlet and discharge ends, a plurality of angularly adjustable vanes mounted within the sleeve for rotation therewith, an operating linkage connected with said vanes within the casing and rotatable with the vanes and sleeve, a member arranged outside of the casing and adapted to reciprocate longitudinally of the sleeve and connected with the operating linkage to actuate the same for angularly adjusting the vanes in unison while the sleeve rotates, means connected with said member to reciprocate the same, and means connected with the sleeve to rotate the same.

6. Dehydrating apparatus comprising a casing adapted to receive a fluid heating medium, a perforated sleeve journaled within the casing for rotation and adapted to receive and discharge material, a plurality of angularly adjustable vanes mounted within the sleeve for rotation therewith, an operating linkage connected with the vanes inside of the casing and rotatable with the vanes and sleeve, a shaft connected with said sleeve for rotation therewith and extending outside of the casing, a member mounted upon the shaft outside of the casing for reciprocation axially of the shaft and sleeve and connected with the operating linkage to actuate the same for angularly adjusting the vanes in unison while the sleeve rotates, means connected with the member to reciprocate the same, and means connected with the shaft to rotate the shaft and sleeve.

7. Dehydrating apparatus comprising a casing adapted to receive a fluid heating medium, a perforated sleeve mounted within the casing for rotation and having material inlet and discharge ends, angularly adjustable vane means arranged

within the sleeve for rotation therewith and adapted to regulate the passage of the material longitudinally through the sleeve during rotation of the sleeve, operating means connected with said vane means inside of the casing and rotatable with the vane means and sleeve, reciprocatory means arranged exteriorly of the casing and connected with said operating means to actuate the same for angularly adjusting the vane means during rotation of the sleeve, and means connected with the sleeve to rotate the same.

8. Dehydrating apparatus comprising a casing adapted to receive a fluid heating medium, a perforated sleeve mounted within the casing for rotation and having material inlet and discharge ends, angularly adjustable sets of vanes arranged within the sleeve for rotation therewith and adapted to regulate the passage of the material longitudinally through the sleeve during rotation of the sleeve, operating means connected with the sets of vanes inside of the casing and rotatable with the sets of vanes and sleeve, reciprocatory means arranged exteriorly of the casing and connected with said operating means to actuate the same for angularly adjusting the sets of vanes in unison during rotation of the sleeve, and means connected with the sleeve to rotate the same.

9. Dehydrating apparatus comprising a casing adapted to receive a fluid heating medium, a perforated sleeve mounted within the casing for rota-

tion and having material inlet and discharge ends, circumferentially spaced sets of angularly adjustable vanes mounted within the perforated sleeve for rotation therewith and adapted to regulate the passage of the material through the sleeve during rotation of the sleeve, operating means connected with the sets of angularly adjustable vanes inside of the casing and rotatable with the sets of vanes and sleeve, a shaft connected with the sleeve for rotation therewith and extending axially of the sleeve and exteriorly of the sleeve and casing, means connected with the shaft exteriorly of the casing to rotate the shaft and sleeve, and non-rotatable reciprocatory means connected with the shaft exteriorly of the casing and connected with said operating means to actuate the same for angularly adjusting the vanes of the sets in unison during rotation of the sleeve.
